(57) **CLAIM**

The ornamental design for a canopy, as shown and described.

DESCRIPTION

FIG. 1 is a side elevational view of a canopy, showing my new design, the opposite side being a mirror image thereof;

FIG. 2 is a front elevational view, the rear elevational view being a mirror image thereof; and,

FIG. 3 is a bottom view looking upward from a horizontal position laying on the bedstead frame surface thereof.

The broken line showing of environmental elements is for illustrative purposes only and forms no part of the claimed design.
